(57) **CLAIM**

The ornamental design for a integrated light emitting diode (LED) pendant lamp, as shown and described.

DESCRIPTION

FIG. 1 is a front elevation view of a integrated light emitting diode (LED) pendant lamp showing the new design; FIG. 2 is a rear elevation view thereof; FIG. 3 is a left side elevation view thereof, the right side being a mirror image;

FIG. 4 is a top plan view thereof;

FIG. 5 is a bottom plan view thereof;

FIG. 6 is a first perspective view thereof;

FIG. 7 is an enlarged version of the top plan view shown in FIG. 4;

FIG. 8 is an enlarged version of the bottom plan view shown in FIG. 5; and,

FIG. 9 is a second perspective view thereof.

1 Claim, 9 Drawing Sheets
